UNITED STATES PATENT OFFICE

2,046,297

ROADWAY JOINT STRIP

Walter F. Schulz, Youngstown, Ohio, assignor to
Truscon Steel Company, Youngstown, Ohio, a
corporation of Michigan

Application August 16, 1933, Serial No. 685,480

16 Claims. (Cl. 94—18)

The present invention relates to improvements on structures of the type covered by reissue patent to Bernard Briody No. 16,202 by opening one or more sides of the "corrugations" of such patent as by slitting and expanding the material to attain the additional advantages hereinafter set forth.

The product covered by said Briody patent has come into extensive commercial use. It has been found to be desirable to employ for the same relatively heavy gauge metal, not that such heavier metal is necessary for the desired formation of the joints in the concrete, but to withstand danger of distortion during transportation and placing of the material before pouring the concrete and to provide greater resistance to displacement of position by the impact of the concrete during pouring.

Further, the product covered by said Briody patent is commonly punched transversely for insertion of the well-known "dowel bars" and vertically through the "corrugations" for the insertion of the well-known "stake pins" where the structure is not held in position by devices other than such pins.

One object of my present invention is to provide not only for the lines of fracture in the original body of the concrete and the interlocking effect between the finally adjacent but separated bodies of concrete as contemplated and achieved by the invention of Briody, but to increase the interlocking effect laterally. By the present invention, the shear value of the interlock between such adjacent bodies of concrete is greater than results from the use of the Briody product because of the main supporting surface and the greater bearing area of the supporting surfaces for the same area of metal in the original blank and the irregularity and diversification of interlocking surfaces resulting from the use of my invention.

Another object of my present invention is to further provide an interlock between the finally adjacent but separated bodies of concrete longitudinally as well as vertically.

Still another object of my present invention is to provide a structure of said Briody type which will furnish the essential rigidity in metal of the same kind but also of lighter gauge and of less area in the blank from which formed for a given depth of metal joint strip, thereby reducing the raw material costs, cost of transportation based on weight, and labor expense in loading, unloading and field installation.

The preferred embodiment of the present in-

vention and the means by which the method of producing it is carried out, is shown in the accompanying drawings wherein:

Figure 1 is a view in elevation of the road joint strip. 5

Figure 2 is a sectional view on the line 2—2 of Figure 1 but showing one of the positioning pegs in place.

Figure 3 is a longitudinal sectional view of a portion of a concrete roadway with the joint strip 19 embedded therein and showing a dowel pin in place.

Figure 4 is a view in elevation of a portion of a blank from which the finished strip is produced.

Figure 4a is an edge view of the same.

Figure 5 is a horizontal sectional view showing the dies and the initial deformation of the blank.

Figure 6 is a face view of the female die member.

Figure 7 is a sectional view on the line 7—7 of Figure 5. 20

Figure 8 is a detailed sectional view on the line 8—8 of Figure 7.

Figure 9 is a horizontal sectional view through the finishing dies and showing the same in separated relation and the product located between the same. 25

Figure 10 is a sectional view on the line 10—10 of Figure 9.

Figure 11 is a detail view in elevation of the finished product. 30

Considering first the article in its completed form, it comprises outer or marginal strip sections 12, and an intermediate strip section 13, the three strip sections being spaced apart and the intermediate section being offset and lying in a plane preferably parallel to and therefore, at one side of the strip sections 12. These strip sections 12, may be in a common plane. Uniting the intermediate section 13, with the sections 12, are webs of zigzag formation designated 14, and alternately united at spaced points with the opposite edges of the intermediate section 13, and inner edges of the outer strip sections 12. As a matter of fact, they are preferably integral therewith, the entire structure being made from a single blank strip or sheet. 35

As will be clear by reference to Figures 2 and 3, the web strips 14, are preferably disposed in angular relation to the strip sections 12 and 13, this angularity being other than a right angle, the webs being arranged in transversely convergent relation toward the intermediate section 13. At intervals, the webs may have aligned portions offset as shown at 15, providing vertical channels through which temporary "stake pins" as 16, may 40

55

be driven to support the strip in position on the roadway base during the pouring of the concrete. It will also be clear that by reason of the relation of the webs to the strips 12 and 13, horizontal spaces are provided in which dowel pins as 17, 5 may be located. However, if desired, the intermediate strip may be punched at intervals as shown at 18, for the reception of such pins.

The strip is placed on the subsurface of the 10 roadway bed in the usual manner and as indicated in Figure 2 and the concrete is then poured, leaving the strip embedded therein as will be clear by reference to Figure 3.

In the structure of the present invention, compared with material commonly used, it is possible 15 to attain in eighteen gauge metal approximately the same rigidity as would result from the use of similar sixteen gauge metal in previous road strips of the Briody type and, on account of reduction in the original width of the necessary blank for the final product of a joint strip of, for instance, six and a half inches in height, and a saving in gauge between sixteen and eighteen gauge metal, to save in raw material required, 20 about thirty-two per cent thereof. As between other gauges and heights, a like ratable saving in material is secured.

The structure of the present invention serves all 25 the functions of the structure of said Briody patent with the following, among other, additional advantages:

In producing the strip the webs are stretched as hereinafter explained and in addition, the angular relation serves to provide a wider strip with 30 less material, thereby effecting a saving in raw material and in weight.

The plane surfaces of the portion 1 may be made to conform as nearly as may be desired to correspond with the plane surfaces of the roadway and thereby produce a relatively stronger 40 mortised joint between adjacent sections of concrete after the predetermined cracking results.

The openings upon the respective sides of the web portions permit the flow of concrete there- 45 through during the process of initial pouring and thereby lessen resistance to variations of pressure of the fluid concrete upon one side or the other and a consequent tendency to displacement.

While the lines of fracture of the concrete will 50 follow the planes of weakness in the concrete determined by the portions 12 and 13, and substantially the lines between sections adjacent thereto as in Briody, the opposition of inclination of the faces of the concrete portions between the 55 opposing inclinations of the portions of the webs 14, between their connecting points will produce transverse interlocking of said portions of concrete and act to prevent longitudinal displacement between the two concrete sections on opposite sides of the joint strip. And there will be sufficient irregularity of the lines of fracture of the concrete passing through the 60 openings to result in greater interlocking effect between the finally separated bodies of concrete 65 both laterally and vertically without change in the otherwise effect of the outline of the main interlocking joint between the adjacent separated bodies of concrete.

By reason of the foregoing, the respective value 70 of the doweling projections is much greater than in structures of previous use vertically while producing a shear value against longitudinal displacement practically non-existent in prior structures.

75 Dowel bars and stake pins as explained, may be

placed through the expanded openings without special punching.

The preferred method by which the strip is produced will be clear by referring to Figures 4-11 inclusive.

A flat elongated strip of sheet of metal as illustrated in Figures 4 and 4a, is provided with four longitudinal lines or rows of slits 19 and 20. The slits in each row are relatively short and are arranged end to end but slightly spaced apart as 10 shown at 21. Those of adjacent rows are alternated. These rows thus define the marginal strip sections 12, the intermediate strip section 13, and the blanks of the webs 14. The slotted blank is entered between the dies 22, 23, one die having 15 a longitudinal rib 24, and the other, a longitudinal groove 25, to receive the same. These are of the width of the central strip section 13, and as will be clear by a comparison of Figures 5 and 7, serve when the dies are brought together, to offset the 20 intermediate section 13, into a plane at one side of and parallel to the plane of the strip sections 12. The die 22, furthermore, is provided with two hill and valley portions 26, on opposite sides of the rib 24, these interfitting with correspond- 25 ing hill and valley portions 27, on the die 23. It will therefore be evident that when the die is brought together and the intermediate strip section is offset, the web blanks 14, will be caused to assume a zigzag formation and in doing so, the 30 material is longitudinally stretched and thus made thinner. In other words, the surface length of each zigzag web is then greater than the surface length of the strip sections 12 and 13. If desired, the die 22, may furthermore, be provided at 35 intervals with punch studs 8, adapted to enter sockets 29, in the die 23, for the purpose of forming dowel receiving holes 18.

The result is an intermediate form shown in Figures 5, 7, and 8, in which the offset relation 40 of the intermediate and marginal strip sections is secured and a zigzag or wavy formation of the webs is produced. This in itself, would produce a joint strip, but the surfaces of the zigzags are vertical and only vertical openings through the 45 webs are thus produced. The sheet, however, remains of the same width, as distinguished from the Briody strip which is narrowed.

Referring now to Figures 9, 10, and 11, the operation on the material is preferably continued, 50 however, by the employment of a second set of dies designated 30 and 31. As shown particularly in Figure 10, the die 30, has a recess 32, located between vertical surfaces 33, the bottom of the recess 32, having a central vertical surface 35, lo- 55 cated between inclined surfaces 36, and the side walls of the recess being also preferably inclined outwardly as shown at 37 and at right angles to the surfaces 36. The die 31, is provided with an outstanding rib 38, having a vertical surface 39, 60 and convergent side faces 40, set at right angles to adjacent back faces 41. These, in turn, terminate at vertical faces 42.

The material in the shape shown in Figures 5, 7, and 8, is placed between these dies 30, and 31, 65 with the intermediate strip section 13, in a position to be pressed against the face 39, of the die 31. When the dies are brought together, therefore, it will be evident that the rib 38, of the die 31, will press the intermediate section 13, between 70 and to the opposite side of the strip sections 12, and at the same time swing the zigzag webs to the opposite side and into an angular relation to the strips 12 and 13. This, therefore, causes the strip sections 12, to be forced apart a greater distance 75

- and thus widens the structure without any addition to the material.
- What I claim, is:
1. A roadway joint strip of metal comprising relatively offset metal strip sections, and an open lattice-like continuous web connecting adjacent offset marginal portions of such sections.
  2. A roadway joint strip of metal comprising relatively offset longitudinal metal strip sections, and a continuous longitudinal substantially zig-zag web strip section connected at intervals to the adjacent offset marginal portions of the strip sections.
  3. A roadway joint strip of metal comprising outer longitudinal strip sections, an intermediate longitudinal strip section offset from the outer sections, and longitudinally extending laterally offset lattice-like web sections connecting the marginal portions of the intermediate strip section with the adjacent portions of the outer strip sections.
  4. A roadway joint strip of metal comprising outer strip sections, an intermediate strip section offset from the outer sections, continuous longitudinally extending and laterally offset lattice-like web sections connecting the outer edge portions of the intermediate strip section with the inner adjacent edge portions of the outer strip sections.
  5. A roadway joint strip of metal comprising outer longitudinal strip sections, an intermediate strip section offset from the outer sections, and longitudinal continuous web sections of zigzag formation laterally disposed with respect to the intermediate and outer strips and having portions connected to the outer edge portions of the intermediate strip section and the inner adjacent edge portions of the outer strip sections.
  6. A roadway joint strip of metal comprising longitudinally disposed strip sections that are relatively offset, and a continuous longitudinally extending web of substantially zigzag formation having portions along one edge connected to one edge of one of the strips and portions along its other edge connected to the adjacent edge of the other strip.
  7. A roadway joint strip of metal comprising longitudinally disposed strip sections that are relatively offset, and a web of substantially zigzag formation having portions along one edge integrally united to one edge of one of the strips and portions along its other edge integrally united to the adjacent edge of the other strip, the side faces of the webs being angularly disposed with respect to the side faces of the strip sections.
  8. A roadway joint strip consisting of a single sheet of metal having outer strip sections located in substantially the same plane, an intermediate strip section offset therefrom and substantially parallel thereto, and webs of expanded metal integral with the strip sections and connecting the same, said webs being disposed laterally to the strip sections and integrally joined thereto at spaced points, and having their side faces disposed in angular relation to the side faces of the strip section.
  9. A roadway joint strip comprising longitudi-
  - dinal strip sections and a web connecting the same and consisting of a strand of longitudinally stretched material united at intervals to the strip sections.
  10. A roadway joint strip comprising longitudinal strip sections located in different planes, and a web of longitudinally stretched metal united alternately and at spaced points to the respective strip sections.
  11. A roadway joint strip comprising spaced longitudinal strip sections, and a web integrally connected at spaced points to the strip sections, of stretched material thinner than the material of the strip sections.
  12. A roadway joint strip comprising spaced longitudinal strip sections, and a web integrally connected at spaced points to the strip sections, of stretched material thinner than the material of the strip sections, said web being of zigzag formation and thereby having a surface length greater than the strip sections.
  13. A roadway structure including adjacent slab sections having a longitudinal tongue and groove interfitting engagement that prevents relative up and down movement, said tongue and groove having transversely disposed zigzag interlocking portions in engagement that prevents relative longitudinal movement between the slab sections.
  14. A roadway joint strip comprising longitudinally disposed strip sections, one being laterally offset from the other, and a longitudinally extending intermediate strip of substantially zigzag formation bridging the space between adjacent edges of the said sections and having its side faces disposed in transverse angular relation to the side faces of the first strip sections, said intermediate strip being joined at its bends alternately to the said adjacent edges of the first mentioned strips.
  15. A roadway joint strip comprising longitudinally disposed substantially vertical upper and lower strip sections, one being laterally offset from the other, the upper strip having its lower edge higher than the upper edge of the lower strip section, and a longitudinally extending substantially zigzag form bridging the space between the strip sections, the high points of one edge of the intermediate strip being joined to the lower edge of one of the first strips, the bottom points of the other edge of the zigzag strip being joined to the top edge of the other of the first strips.
  16. A roadway joint strip comprising spaced upper and lower longitudinal outer strip sections located in a substantially vertical plane, an intermediate strip section located in a substantially vertical plane at one side of the upper and lower strip sections, and continuous longitudinally disposed intermediate zigzag strip sections lying in angular relation to and bridging the spaces between the edges of the intermediate strip section and the upper and lower sections, the portions at the bends of said zigzag sections being joined to the adjacent edges of the upper, lower and intermediate strip sections.

WALTER F. SCHULZ.
